METHOD OF AND APPARATUS FOR TEMP-
ERATING AIRJohn F. Hoffman, Omaha, Nebr., assignor to
Baker Ice Machine Co. Inc., Omaha, Nebr., a
corporation of Nebraska

Application April 28, 1930. Serial No. 448,655

10 Claims. (Cl. 62--120)

My invention relates to a method of and apparatus for refrigeration, and more particularly to a method of tempering the air in an insulated compartment, for example in an ice box.

3 In the common type of meat coolers a substantial proportion of the insulated housing forming the cooler, for example one-third of the upper portion thereof, must be reserved to hold a sufficient quantity of ice to cool the box. The melting of the ice causes cold air to move downwardly throughout the box and warm air therefore rises to melt the ice. A materially larger housing is therefore required than necessary for containing the commodities to be cooled and excessive 10 labor and frequent opening of the box are involved in supplying the housing bunker with ice.

The water resulting from melting of the ice must be disposed of whereby an inordinate extent of relatively non-conductive supporting 20 members or bunker floors is interposed between the cooling medium and commodities in the box.

It is apparent also that maximum cooling effect is only afforded when the bunkers are well supplied with ice. When coils supplied with a 25 refrigerant are substituted for the ice, the pipes become covered with frost, and efficiency is reduced, and must be defrosted, thus involving opening of the box and warming up of the contents.

30 The principal objects of my invention therefore are to provide a method of refrigerating a space whereby the requirement of ice containing bunkers and similar bulky refrigerating means may be done away with, to supply the humidifying effect of ice refrigeration by the means employed for effecting refrigeration, to avoid the accumulation of frost on the refrigerating means whereby frequent treatment is required for removing frost, and to provide for automatic operation and control of refrigerating elements.

In accomplishing these and other objects of my invention, I have provided improved details of structure, the preferred forms of which are illustrated in the accompanying drawings, 45 wherein:

Fig. 1 is a vertical transverse section of the housing equipped with apparatus in accordance with my invention.

Fig. 2 is a perspective view of a modified form 50 of apparatus, a casing wall being partly broken away to disclose contained elements.

Fig. 3 is a vertical section from front to back of the apparatus shown in Fig. 2.

Fig. 4 is a side elevation of rollers for pressing 55 moisture from moving belts.

Referring in detail to the drawings:

1 designates one of the side walls of a housing including opposite vertical walls 2 and 3 and top and bottom walls 4 and 5, representing, for example, a meat cooler to which access may be had 60 through a door, not shown.

In ordinary practice, the space in the cooler is occupied partly by perishables, but a substantial portion at the upper end is required for storing ice, or for refrigerating pipes, for cooling the perishables.

In my improved method of refrigeration, I provide a tank 6 at one end of the chamber adjacent the end wall 2 of the housing including a bottom wall 7, the tank being reinforced and supported by a relatively thick wall 8, the vertical end edges of the tank engaging the front and back side walls of the housing, and the upper edge being spaced from the top of the housing.

The tank is adapted to contain a liquid such as 75 brine susceptible to cooling to a relatively low temperature without freezing, and refrigerating coils 9 are arranged adjacent the walls of the tank, which may be supplied with a refrigerant to cool the brine and maintain the same in cold 80 condition.

The coils are preferably arranged in vertical planes in spaced series to provide a passage therebetween for vertical spaced branches or runs 10 and 11 of an endless belt anchored and movable 85 on a roller 12 having a shaft 13 rotatably mounted in journal brackets 14 fixed to the floor of the tank and housing, and rollers 15 and 16 rotatable in journals 17 and 18 respectively on a bracket 19 fixed to the wall 3, and a roller 20 supported by 90 a bracket 21 from the wall 2.

The rollers 15 and 16 supported by the single bracket above the tank cause the belt to move downwardly and upwardly over the lower roller in vertical paths, and the single roller at the opposite end of the housing is supported on bearings located in a plane between the planes of the bearings of the pair of rollers, whereby the upper horizontal run 22 of the belt may move close to the top of the housing, and the lower run 23 100 will move across the housing and throughout substantially the entire length of the same.

The belt is caused to move preferably by providing a pulley 24 on the roller shaft of the single roller, mounting a motor 25 on a shelf 26 fixed 105 to the wall 3 of the housing and running a belt 27 from the motor shaft pulley 28 to the roller pulley.

The motor may be controlled by a thermostatically operating device mounted on the wall of the 110

housing including a switch box 29 from which conductors 30 and 31 lead to the motor, whereby changes of temperature in the chamber may effect operation of or suspension of operation of the motor.

In order to remove excess moisture picked up by the belt while the same is passing through the tank, I may provide a roller 32 mounted in fixed position adjacent one face of the vertical branch 10 of the belt and a roller 33 engaging the opposite face of the belt, the rollers being supported by suitable brackets such as end plates 34 and blocks 35 slideable in slots 36 in the plates supporting the roller 33 whereby the pressure of the rollers may be adjusted.

In the modified mode of employing the method shown in Figs. 2 and 3, the liquid containing refrigerating tank comprises a case including a rear wall 37 having an opening 38 adjacent its upper end and provided with a chute-like air inlet 39 and a front wall 40 provided with a spout-like neck or extension 41 communicating with the tank above the coils and level of water in which the coils are immersed, having a laterally directed mouth 42, the tank being closed by a top 43.

The tank is relatively wide, having preferably substantially the same width as the space to be cooled, whereby a sheet or stream of air passing from the spout may have the same width as the space.

A bracket 44 supports a motor 45 adjacent the opening and operates a fan 46 therein for blowing air through the tank and expelling the same through the spout.

In this form of the apparatus for employing the method, two or more sets of belts 47 and 48 may be employed running on rollers 49-50 and 51-52 respectively, at the upper and lower ends 40 of the tank, in the path of the current of air moving through the same, and the belt preferably comprises relatively slender flexible members 53 such as cords or the like, among which the air may move relatively freely to pick up cold therefrom.

In this form of apparatus, one set of rollers may be operated from the other by means of a belt 54 running on pulleys 55 within the tank at the ends of roller shafts 56 mounted in walls of the tank, and one of the rollers may be rotated through a flexible shaft 57 actuated by the motor.

In the form of the invention illustrated in Fig. 1, the belt moving downwardly then upwardly through the refrigerated liquid is cooled thereby, and preferably is moved downwardly over the outer coil and upwardly over the inner coil, whereby the laterally moving lower horizontal run of the belt presents its surface downwardly to the chamber to exchange heat with the air therein and the warmer upper horizontal run or branch of the belt moves retractively adjacent the relatively warm top of the housing back to the refrigerating tank. The warm air in the chamber will rise into contact with the belt and being cooled thereby will then tend to fall and move through the chamber.

Circulation of air in vertical paths will thus be set up, and when the belt has substantially the same width as the chamber there will be vertical currents of air moving constantly throughout the entire space of the chamber.

Not only will the contents of the chamber thus be effectually cooled but modification of humidity will also be effected since moisture will be taken up by the moving belt due to condensation of

vapors contacting the cold surfaces of the belt, and the moisture will be carried back to the tank. The character of liquid in the tank modified by such collected moisture may be adjusted to maintain its desired function.

In employing the form of apparatus illustrated in Figs. 2 and 3, the case may be located in any desired and suitable relation with a space to be cooled, for example, within a meat cooler. The refrigerating coils being supplied with a refrigerant and liquid being provided in the tank to cover the coils, when the rollers are set in motion to move the belts and the fan is operated, air will be drawn by the fan through the opening and moved through the tank over the belts and discharged through the spout.

The air will exchange heat with the belts and the air thus refrigerated will move throughout the chamber to set up circulation therein.

The tank illustrated in Figures 2 and 3 may extend substantially to the top of the chamber when a housing such as a meat cooler illustrated in Fig. 1, is to be cooled, whereby a relatively wide stream of air will be impelled across the top portion of the chamber to the opposite wall, thus forming a cold blanket against which the rising warmer air in the chamber will impinge to be cooled and set up vertically moving currents of air in the chamber.

The moving stream of impelled air may impinge on the opposite wall and move downwardly therealong and be diverted outwardly therefrom to set up incidental currents of relatively cool air in the space occupied by the perishables.

The fan, both by suction and by the effect of driving air through the chamber, will tend to draw air from the chamber so that the air will be thoroughly circulated.

It is apparent that the inlet neck may communicate with outside atmosphere, that the side mouth 42 of the tank may be located to deliver a stream of cold air to a space to be cooled, and that the space may or may not have an outlet, according to the particular requirements of refrigeration of the space to be cooled.

What I claim and desire to secure by Letters Patent is:

1. A method of tempering air of a compartment consisting of passing a tempering member through the compartment, and controlling movement of the tempering member according to the temperature to be maintained in the compartment.

2. A method of tempering air consisting of passing a cold transferring member alternately through a cooling medium and through an area to be cooled, and controlling movement of said cold transferring member according to the temperature to be maintained in said area.

3. The method of tempering air including moving a belt horizontally across a compartment adjacent the top wall thereof, and applying cooling influence to the belt adjacent the side wall of the compartment.

4. The method of tempering air confined in a compartment including moving an endless belt horizontally across the top portion of the compartment and vertically across one end of the compartment, and cooling the belt while the same is moving vertically.

5. The method of tempering air including moving a belt in a path adjacent a horizontal wall of a compartment, and applying a tempering influence to the belt adjacent one end of the path for tempering layers of air adjacent the belt to effect

vertical circulation of air in the compartment.

6. A method of tempering air to effect vertical circulation of air in a closed compartment including effecting movement of a cooled tempering

5 member horizontally across the compartment in a path parallel with and closely adjacent to the top wall of the compartment for cooling relatively warm air rising in the compartment to set up vertical circulation of air in the compartment, and 10 controlling movement of said tempering member according to the temperature to be maintained in the compartment.

7. Apparatus for tempering air in a closed compartment including a member movable in a horizontal path adjacent a horizontal wall of the compartment, and means for tempering the member to temper air contacting said member for setting up vertical circulation of air in the compartment.

20 8. Apparatus for tempering air in a compartment including an endless belt moving in a path including a horizontal portion adjacent the top wall of the compartment and a vertical portion

adjacent one end of the compartment, and means adjacent the vertical portion of said path for cooling the belt.

9. Apparatus for tempering air in a compartment including a liquid containing tank at one end of the compartment, horizontally spaced rollers at opposite ends of the compartment adjacent the top thereof, a roller mounted in the tank, an endless belt supported by said rollers to form horizontal runs adjacent the top of the compartment and vertical runs moving in liquid in the tank, means for moving the belt, and means for cooling liquid in the tank.

10. Apparatus for tempering air in a closed compartment including a belt movable in a horizontal path across the compartment, means for tempering the belt for exchanging heat with air in the compartment to set up vertical circulation of air in the compartment, means for driving the belt, and means responsive to changes of temperature in the compartment for controlling the speed of the driving means.
